UNITED STATES PATENT OFFICE.

CHARLES B. SHAEFF, OF NORRISTOWN, PENNSYLVANIA.

AUXILIARY-AIR INLET.

1,398,805.

Specification of Letters Patent.

Patented Nov. 29, 1921.

Application filed July 29, 1919. Serial No. 314,124.

To all whom it may concern:

Be it known that I, CHARLES B. SHAEFF, a citizen of the United States, residing at Norristown, in the county of Montgomery and State of Pennsylvania, have invented 5 certain new and useful Improvements in Auxiliary-Air Inlets, of which the following is a specification.

This invention relates to improvements in 10 engine attachments, and more particularly to a device designed for attachment between the coupled portions of an engine intake manifold and carbureter for admitting an additional supply of air to the manifold and thereby economize in the consumption of liquid fuel and render the explosive mixture 15 more readily combustible.

The invention has for its primary object 20 to provide an attachment of this character which is exceptionally simple in construction and convenient and effective in use, the admission of air to the manifold being controlled entirely by a single conveniently accessible air valve supported upon the attachment.

Another object is the provision of an attachment of this character in which the supply of auxiliary air is distributed in such manner as to secure maximum efficiency in 30 the vaporization of the liquid fuel.

With these and other objects in view as will appear as the description proceeds the invention comprises the novel features of construction, combination of elements and 35 arrangements of parts which will be more fully described in the following specification as set forth with particularity in the claims appended hereto.

In the drawings:

40 Figure 1 represents a longitudinal sectional view through the attachment.

Fig. 2 represents an edge elevation thereof.

Fig. 3 represents a longitudinal sectional view taken at right angles to Fig. 1, looking downwardly.

Fig. 4 represents a transverse sectional view through the attachment.

Fig. 5 represents a fragmentary detail 50 sectional view with the plane of the line 5—5 of Fig. 3.

Referring to the drawings in detail wherein similar reference numerals designate corresponding parts throughout the several views, numerals 5 indicate the body of the

attachment which is preferably shaped in conformity with the coupling flanges ordinarily provided with the terminals of an engine carbureter and intake manifold, and is provided terminally with apertures 6 for 60 accommodating the bolts by which the carbureter and manifold are connected, such bolts being utilized to securely clamp the attachment in operative position between these parts. The central portion of the 65 body is provided with an aperture 7 of the same internal diameter and registering with the bore of the manifold providing a passageway for the gaseous fuel incident to its passage to the intake manifold of the explosive engine in connection with which the attachment is used.

A foraminous member 8 constructed of wire screen of suitable mesh is engaged with the top face of the body 5 and is clamped 75 in position between the body and the adjacent terminal flange of the inlet manifold (not shown). The central portion of the screen which overlies the central opening 7 in the body is of semi-spherical shape 80 presenting an increased area for contact with the gas passing therethrough.

The body 5 is formed with opposed enlargements 9 and 10 which project laterally thereof and are provided with internal air 85 chambers 11, having open terminals receiving the adjacent terminals of a substantially U-shaped air pipe 12 which extends about one terminal of the body 5 and is designed to conduct air from the 90 chamber of the lateral enlargement 10 to the chamber of the lateral enlargement 9 whereby air is supplied through the latter.

The wall of the opening 7 is formed with opposed groups of air ports 13, one group 95 having communication with the chamber of the lateral enlargement 9 and the other group having communication with the internal chamber of the enlargement 10. As suggested in Fig. 4, the respective groups 100 of apertures or ports 13 are disposed obliquely, gradually rising from the outer terminals which communicate with the chambers 11 to their inner discharge terminals which communicate with the openings 7, 105 thus causing the air discharged therefrom to be directed upon the semi-spherical portion of the member 8 and materially assist in the evaporation of such liquid fuel which may have condensed thereon.

Atmospheric air is admitted to the chamber 11 of the enlargement 9 through a main air inlet port 14 and a pivoted shutter valve 15 is arranged to move across the ports 14 to control the admission of air thereto. As will be clearly evident, by varying the position of the shutter valve 15 with relation to the port 14, the latter may be restricted to control the quantity of air admitted to 10 the attachment in order to secure maximum working efficiency of the engine to which the attachment is applied.

The shutter valve 15 is provided with a radial extension 16 constituting a handle 15 for convenience in adjustment and the terminal of the extension is preferably apertured to receive a rod or other actuating device (not shown) which may be extended to a point conveniently near the driver of 20 the vehicle, in case the attachment is applied to the engine of a motor vehicle. The top face of the body 5 is formed with an enlargement or boss 17 receiving a screw 18 upon which the medial portion of the 25 extension 16 is pivotally secured, thereby affording a pivotal support for the valve 15 and sufficient friction is preferably developed at the point of attachment of the valve to the body 5 as to secure the valve 30 in adjusted position against accidental displacement during vibration of the engine incident to operation thereof.

What I claim is:

1. An attachment of the class described comprising an elongated body member having 35 attaching apertures in its end, and a central opening between said apertures adapted to register with the bore of an engine manifold when applied, a wire screen atomizer mounted over said opening, said body having longitudinally extending air chambers formed on opposite sides thereof, said chambers being closed at one end and open at the other, a pipe connecting the open ends of said chambers, one of said 40 chambers having a valve controlled air inlet and each having a plurality of air passages communicating with the central opening in said body.

2. An attachment of the class described 50 comprising a body having a central opening to register with the bore of an engine manifold when applied, a semi-spherical wire screen atomizer mounted over said opening with its concaved face positioned 55 inwardly, said body having a plurality of obliquely arranged air passages mounted to discharge against the inner face of the summit of said atomizer whereby the air and gas are thoroughly commingled and 60 atomized.

In testimony whereof I affix my signature hereto.

CHARLES B. SHAEFF.
